[57] CLAIM

The ornamental design for a fish hook extractor, as shown and described.

DESCRIPTION

FIG. 1 is a perspective view of a first embodiment of my new design for a fish hook extractor;
FIG. 2 is a front view thereof;
FIG. 3 is a left side view thereof;
FIG. 4 is a right side view thereof;
FIG. 5 is a rear view thereof;
FIG. 6 is a top view thereof;
FIG. 7 is a bottom view thereof;
FIG. 8 is an enlarged view of a portion of the fish hook extractor of FIG. 2;
FIG. 9 is a left side view thereof;
FIG. 10 is a right side view thereof;
FIG. 11 is a bottom view thereof;
FIG. 12 is a front view of a second embodiment of my new design for a fish hook extractor, with the rear view being a mirror image thereof;
FIG. 13 is a left side view thereof;
FIG. 14 is a right side view thereof;
FIG. 15 is a top view thereof; and,
FIG. 16 is a bottom view thereof.
